UNITED STATES PATENT OFFICE.

SAMUEL PERRON, OF MENDON, MASSACHUSETTS, ASSIGNOR TO ALEXANDER STEINERT, OF BOSTON, MASSACHUSETTS.

COIN-CONTROLLED TALKING MACHINE.

Application filed January 3, 1921. Serial No. 484,709.

This invention relates to talking machines and has for an object to provide a talking machine with a simple and efficient means by which it is caused automatically to present the contents of a record upon the deposition of a proper coin in a suitable receptacle; and to repeat the presentation for each coin deposited.

This invention has particular reference to talking machines adapted to present the contents of disc records and a further object is to provide a disc-record machine with coin-controlled means by which it is caused to repeat the presentation of the contents 10 of a disc record for each coin deposited in its receptacle.

A further object is to provide existing disc-record machines with coin-governed starting, stopping and repeating means as 20 an attachment.

Existing disc-record machines are provided with a controlling element by which the machine is started and stopped, and may be provided with a repeating attachment 25 by which the machine is adapted repeatedly to present the contents of its record; and a further object is to provide means to operate said controlling element which is arranged to be governed by a coin-operated device and also by a movable component of the talking-machine.

A further object is generally to improve the construction and operation of coin-controlled, automatically-repeating talking machines.

Fig. 1 is a perspective view of a disc record, cabinet talking machine embodying my invention.

Fig. 2 is a diagrammatic representation 40 of the essential elements of the talking machine and the controlling system therefor embodying my invention.

Fig. 3 is a plan detail of the talking machine of Fig. 1.

Fig. 4 is a front elevation of the controlling means for the starting and stopping lever of the talking machine in the normal or unoperated position thereof.

Fig. 5 is a similar view of the controlling 50 means in an operated position.

Fig. 6 is a side elevation, in detail, of the tone arm of the talking machine and the tone-arm controlled switch for the controlling means illustrated in section.

Fig. 7 is a plan section of the switch of 55 Fig. 6 taken along line 7-7 of Fig. 6.

Fig. 8 is a perspective view of the repeating attachment.

Fig. 9 is an enlarged detail, partly in section, of the raising and lowering screw and 60 associated elements of the repeating attachment.

Fig. 10 is a sectional detail of a coin-receptacle.

As here shown, my invention is applied 65 to a disc-record cabinet talking machine of the Victor type although it is applicable to other machines.

The talking machine comprises the cabinet 10 having the floor 11 in the top portion thereof above which the record turn-table 12 is rotatably supported. The usual tone-arm 13 is pivotally supported by the floor at one side of and is movably extended 70 above the turn-table. A starting and stopping element comprising a manually-operable lever 14 is supported above the floor adjacent the periphery of the turn-table and is arranged to engage and release the turn-table, in a spring-propelled machine, 75 to stop movement of the turn-table or to permit it to rotate, and to control a suitable motor-switch if the machine is electrically operated.

Turn-table operating mechanism is disposed below and concealed by the floor of 80 the cabinet.

It is highly desirable that all possible operating and control elements of the machine be concealed and for this purpose 85 the controlling-mechanism, which comprises a part of my invention, is disposed beneath the floor 11.

In carrying out my invention, I provide 90 two means by which to govern the operation of the machine. One of said means comprises a coin-receptacle which may be attached to the cabinet of the machine or may be remotely disposed with respect thereto as herein illustrated. Said receptacle 95 may have the electric contact-members of a switch therein which are adapted to be moved and momentarily held in electrical engagement upon the deposition of a coin 100 in the receptacle whereby to cause the talking machine to begin the presentation of the contents of its record. Said other means 105 may be controlled by a movable component

of the machine and may operate to stop the machine after the finish of the presentation of the contents of the record and preferably after the reproducer has been returned to the beginning of the story on the record but also preferably before it has again engaged the record.

The controlling-mechanism adapted to be operated by said governing means is disposed below and supported by said floor 11 and is arranged to move the starting and stopping lever 14 in one direction to start or stop the record turn-table when governed by one of said governing means and to move said lever 14 in the opposite direction to stop or start the record turn-table when governed by said other means.

Said controlling-mechanism comprises the supporting or back-board 16 secured to the under side of said floor 11 by screws 17 and disposed, preferably, in one corner of the cabinet as indicated in the dotted lines, Fig. 3.

The floor 11 is formed with a slot 18 therein disposed below said lever 14 and a cam-member 19 is pivoted on the post 20 to said back-board 16 beneath said slot. Said lever 14 is formed with a hole 21 therethrough and said cam-member is provided with an extension 22 which is loosely received in said hole. An angular movement of said cam-member about its pivot from one extreme position to the other in one direction serves to move said lever 14 from starting to stopping position and a movement to the extreme position in the reverse direction serves to move said lever from stopping to starting position. The lower face of said cam-member is formed with two V-shaped cam-recesses 23 and 23^a therein on each side of the middle V-shaped projection 24, the apex of which is substantially in line with the pivot and extension 22 of the cam-member. The operating means for said cam-member includes the electro-magnet 25 secured to said back-board 16 and the armature 26 of said electro-magnet which is pivotally disposed below the poles of the electro-magnet on the pin 27 and normally rests in retracted position against the stop 28. Said armature is formed with an extension 29 which rests against the lower face of or is otherwise, preferably pivotally, secured to a slide member 30; and said member is vertically movably disposed beneath said cam member 19 in the guide ways 31 carried by the back-board 16. Said guide-member 30 has a cam-engaging member 32 extended upwardly therefrom and pivotally connected thereto at 33. A spring-element 34 secured to said members 30 and 32 serves normally to hold them in alignment and will permit said member 32 to be angularly displaced about its pivot, as illustrated in Fig.

5, to enable it operatively to engage said cam-member 19 and will thereafter return it into vertical position. Said member 32 is formed with the reduced end-portion 32^a adapted to enter said cam-recesses 23 and 23^a in said cam-member and move said member alternately into the extreme positions illustrated in Figs. 4 and 5.

Said cam-member 19 is adapted normally to be in one or the other extreme position. Assuming it to be originally in the position illustrated in Fig. 4, the energization of said electro-magnet 25 caused by one of its governing means will cause the armature 26 to move the slide-member 30 upwardly and cause the extremity of the member 32 to enter the cam-recess 23 and contact with the bottom thereof, said member 32 pivoting on its member 30 for this purpose. A further upward movement of said member will cause said cam-member 19 to be rotated clock-wise on its pivot to move the starting and stopping lever 14, into, say stopping position, as indicated in Fig. 5. The governing means are arranged but momentarily to cause the energization of said electro-magnet 25 and when the control-circuit is interrupted, said slide member 34 will return by gravity to its low or retracted position. Said cam-member 19 now presents its other cam-recess 23^a to be engaged by the member 32 and the succeeding operation of the electro-magnet due to the control thereof by the other governing means, will cause said cam-member to be moved in a counter-clockwise direction to move the lever 14 to, say, starting position.

For spring-propeller talking machines said starting and stopping lever 14 may be provided with a brake-arm 35 having a brake-shoe 36 at the extremity thereof which is adapted frictionally to engage the inner periphery of the rim of the record turn-table to hold it against rotation and when said shoe is free from the turn-table said table is free to rotate. For talking machines operated by an electric motor, said lever 14 may also have the brake-arm 35 and in addition is arranged to operate a switch which is adapted to control the circuit including the motor of the talking machine. As here shown, the switch comprises the contact members 37 and 38 disposed beneath the floor 11 and included in the motor circuit 39 wherein the motor is represented at 39^a. A cam 40 fixed on the lower end of the pivot 41 of said lever 14 beneath the floor is adapted to move said switch-members into closed position to cause the motor to operate.

The coin-receptacle comprising one of the governing means for the controlling-mechanism may comprise the box 45 having a coin chute 46 therein which is open at its upper end to receive a coin of suitable denomination. A movable switch member 47 is disposed be-

neath the inner end of the coin chute and is adapted to be depressed by the weight of a coin falling upon it into contact with a stationary switch member 48 which is disposed below said movable member thereby to complete the control circuit 49 including the electro-magnet 25 and the source of energy 50 which latter may comprise a few dry cells contained in the cabinet of the talking machine. The coin chute has a slot 51 in the lower end of a side wall thereof through which the coin is adapted to roll from the movable switch member into the bottom of the box and the movable switch member 47 is thereupon raised by the counter-weight 52 or equivalent into normal position free from contact with the stationary switch member. The switch members are but momentarily in engagement but the duration 20 of contact is made sufficient to cause operation of the controlling mechanism.

The talking machine is provided with means automatically to return the reproducer thereof to the beginning of the story 25 on the record.

Said means includes the attachment including the cylinder 55 adapted removably to be secured to that portion of the turn-table shaft 56 extended above the turn-table. 30 Said cylinder is formed with the reverse screw threads 57 and 58 communicating with the annular groove 59 in the lower portion thereof. A casing 60 loosely encloses said cylinder and its lower end is secured to a curved arm 61 which extends over and above the turn-table and any record thereon and its end is secured to the floor 11 through the adjusting screw 62. Said casing 60 is formed with the vertical slot 63 therein and the end of a second and similarly curved arm 64 encircles said casing and has a projection 65 which is extended through said slot for engagement with the screw threads 57 and 58 of said cylinder 55. Said arm 64 extends above said arm 61 and is pivoted to the frame 66 carried by said adjusting screw 62. Said arms are disposed below the tone arm 13 and said tone arm is adapted to rest upon and slide over said upper arm 64. When the reproducer is playing the record the upper arm 64 is adapted to rest in a horizontal position with the projection 65 thereof in the groove 59 in the cylinder 55. When the reproducer has arrived at the end 55 of the record the arm 64 is automatically tilted upward for engagement with one of said threads as 58, and said rotating cylinder thereupon raises the inner end of said arm 60 and causes the tone arm to slide downwardly thereon toward the beginning of the record. The arm 64 will then descend in the other screw thread, as 57, and ordinarily, will lower the reproducer into engagement with the record, thereby to cause the presentation 65 of the contents thereof automatically to be

repeated. A pivoted lever 68 which is adjustably received in the slot 69 of said lower arm 61 is adapted to be engaged by the tone-arm 13 as it is moved by the record and tilted to raise the upper arm 64 into engagement with the screw-threads of the cylinder 55; and a stop-member 70 adjustable along the length of said upper arm 64 serves to position the tone-arm for the engagement of the reproducer with the beginning of the story on the record.

The tone-arm 13, as it slides down said arm 64 is adapted to operate the other governing means for the controlling mechanism and cause the turn-table to be stopped before the reproducer has again engaged the record.

The second governing means comprises the switch enclosed in the casing 71 and disposed on the floor 11 to one side of the turn-table 12 and under the tone-arm. Said switch may comprise the stationary switch member or post 72 and the movable switch member 73 pivotally connected at 74 to the insulating base 75 and extended outwardly through a slot 76 in said casing 71. Said movable switch member 73 is arranged to be engaged by the pin 77 secured to and depending from the tone arm 13. Said member 73 is made somewhat resilient and said pin is adapted to engage and move it into engagement with the stationary switch member 72 when the tone arm is moving outwardly and preferably when the tone arm is near its outermost position and then pass by said movable switch member. The resiliency of said movable switch member serves to cause it to spring away from the stationary member when the tone arm releases it, thereby to open the control circuit. As said tone-arm is moved forward on its playing stroke, said pin 77 is adapted to engage said member 73 and move it away from the stationary switch member 72 against the wall of the slot 76 in the casing and then move clear of it, due to the flexing of said movable switch member.

Said switch is connected in multiple with said coin-receptacle in the control circuit 49 and at each operation will cause the operation of the controlling mechanism including the electro-magnet 25. Said switch is so disposed with reference to the tone-arm that said tone-arm will close the switch to stop the rotation of the turn-table preferably before said arm 64 of the repeating device has begun to lower the reproducer toward the record.

The various components of the apparatus are so arranged that normally the machine is at rest with the reproducer in raised position above the beginning of the story on the record. The act of depositing a coin in the coin-box 45 serves to close momentarily the switch members 47 and 48 there-

by to energize the electro-magnet 25. The starting and stopping lever 14 is thereupon moved away from engagement with the turn-table if the machine is a spring-operated machine, and closes the switch comprising the contact arms 37 and 38 if the machine is electrically driven, thereby to close the motor circuit to cause the turn-table to be rotated.

10 The reproducer is moved by the record inwardly from the periphery thereof on the playing stroke and eventually engages the trip-lever 68. The repeating or reproducer-returning device is thereby set in operation 15 and the tone-arm is caused to slide down the arm 64 by gravity and return to its normal position against the stop 70. In its movement down said arm it engages and closes momentarily the switch comprising 20 the switch members 72 and 73. The controlling mechanism including the electro-magnet 25 is thereupon again operated to move the starting and stopping lever 14 into engagement with the turn-table or 25 break the motor circuit, or both, and stop the machine with the reproducer in raised position above the beginning of the story on the record.

The deposition of a second coin in the 30 coin receptacle will cause the machine to operate on a second cycle of operations which will be repeated for each coin deposited.

A plurality of coin receptacles may be 35 provided if desired which will be connected in multiple or otherwise in the control circuit 49 and disposed conveniently about the room containing the talking machine.

I claim:

40 1. A talking machine having the combination of a reproducer, raising and lowering means for the reproducer automatically operable to raise the reproducer from the record at the end of the story thereon and 45 transfer it into position above the beginning of the story, said means including means which can be set to vary the position of the reproducer on the record at which said raising means becomes effective, 50 electrically-actuated starting and stopping means for the machine, remotely-disposed means governing the operation of said electrically-actuated starting and stopping means to effect the starting of the machine 55 and means controlled by the movement of the reproducer to govern said electrically-actuated starting and stopping means to effect the stopping of the machine with the reproducer in position above the beginning 60 of the story on the record and free from engagement with the record.

65 2. A talking machine having a control lever movable into one position to start the machine and movable into a second position to stop the machine, electro-responsive means

to move said lever alternately into both positions and dual means to govern said electro-responsive means.

3. A talking machine arranged to repeatedly present the contents of a record having 70 a control lever movable into one position to start the machine and movable into a second position to stop the machine, electro-responsive means to move said lever alternately into both positions, and dual means 75 arranged alternately to govern said electro-responsive means.

4. A disc record talking machine comprising a floor, a turn-table rotatably mounted above said floor, a tone-arm movably disposed above said turn-table, a starting and stopping lever pivotally supported above said floor, electro-responsive means disposed below said floor having a component operatively engaged with said lever to move it into starting and stopping positions, means to control said electro-responsive means to start the machine and means governed by a movable element of said machine to control said electro-responsive means to stop the 90 machine.

5. An attachment for disc-record talking machines having a movable element and a starting and stopping lever, said attachment comprising electro-responsive means removably connected with said starting and stopping lever, and constructed and arranged to move said lever alternately between starting and stopping positions, means, to operate said electro-responsive means for the starting of the machine, and a device arranged to be governed by the movable element of the machine to operate said electro-responsive means for the stopping of the machine. 95

6. An attachment for disc-record talking machines having a starting and stopping lever, said attachment comprising electro-responsive means removably connected with said starting and stopping lever, and constructed and arranged to move said lever alternately between starting and stopping positions, a manually operable switch to control the energization of said electro-responsive means for the starting of the machine, and a switch governed by the tone-arm of the machine to control the energization of said electro-responsive means for the stopping of the machine. 100

7. An attachment for a disc-record talking machine having a starting and stopping lever, said attachment comprising a pivoted lever adapted for removable connection with said starting and stopping lever, electro-responsive means to move said lever alternately in both directions, and dual means to govern the operation of said electro-responsive means. 110

8. An attachment for disc-record talking machines having a starting and stopping lever, said attachment comprising a pivoted 115

cam-lever arranged for removable engagement with said starting and stopping lever, said lever being formed with two contiguous cam-notches, and electro-responsive means engageable alternately with both of said notches to move said cam-lever alternately in both directions.

9. An attachment for disc-record talking machines having a starting and stopping lever, said attachment comprising a pivoted cam-lever arranged for removable engagement with said starting and stopping lever, said cam-lever being formed with two contiguous cam-notches, a slide engageable alternately with said cam-notches and electro-responsive means to operate said slide.

10. An attachment for disc-record talking machines having a starting and stopping lever, said attachment comprising a pivoted cam-lever arranged for removable engagement with said starting and stopping lever, said cam-lever being formed with two contiguous cam-notches, a slide engageable alternately with said cam-notches, said slide having two pivotally connected components and means to maintain said components normally in alignment, and electro-responsive means to operate said slide.

11. An attachment for disc-record talking machines having a starting and stopping lever, said attachment comprising a pivoted cam-lever arranged for removable engagement with said starting and stopping lever, said cam-lever being formed with two contiguous cam-notches, a slide alternately en-

gageable with said cam-notches, said slide having two pivotally connected components and means to maintain said components normally in alignment, ways in which said slide is movable and an electro-magnet having its armature in engagement with said slide whereby to operate it.

12. A talking machine having a floor, a turn-table adapted to receive a disc record rotatably supported above said floor, a tone-arm pivotally supported above said turn-table, a starting and stopping lever pivotally supported above said floor, electro-responsive means disposed beneath said floor having a component extended through a slot therein and connected with said lever to move it to start and stop the machine, a switch supported on said floor beneath said tone-arm arranged to be operated by said tone-arm on its return stroke to control said electro-responsive means to stop the machine, and a second switch arranged to operate said electro-responsive means to start the machine.

13. A talking machine having a control lever movable into one position to start the machine and movable into a second position to stop the machine, electro-responsive means to move said lever alternately into both positions, and means for governing the operation of said electro-responsive means including means governed by a movable element of the machine.

In testimony whereof, I have signed my name to this specification.

SAMUEL PERRON.
